CLAIM

The ornamental design for a “pressure washer frame”, as shown and described.

DESCRIPTION

FIG. 1 is a front, top perspective view of a pressure washer frame.

FIG. 2 is a front view of the pressure washer frame of FIG. 1.

FIG. 3 is a rear view of the pressure washer frame of FIG. 1.

FIG. 4 is a left side view of the pressure washer frame of FIG. 1.

FIG. 5 is a right side view of the pressure washer frame of FIG. 1.

FIG. 6 is a top view of the pressure washer frame of FIG. 1; and,

FIG. 7 is a bottom view of the pressure washer frame of FIG. 1.

The features shown in broken lines form no part of the claimed design.

The lighter solid lines denote surfaces and contours. Line shading is not surface ornamentation.
